CATHODE-RAY TUBE APPARATUS WITH PARTIAL DIRECT CURRENT RESTORATION

Charles E. Moore, Queens Village, N. Y., assignor to Radio Corporation of America, a corporation of Delaware

Application September 21, 1950, Serial No. 186,039

5 Claims. (Cl. 343—11)

My invention relates to cathode ray tube indicators and pulse-echo radar systems and particularly to systems in which means is provided for switching to different range scales, such as from a twenty mile scale to a forty mile scale.

It has been found in practice that the picture intensity on the cathode ray indicator tube tends to change when the radar system is switched from one range scale to a different range scale. The reasons for this will be discussed hereinafter.

An object of the present invention is to provide an improved method of and means for obtaining substantially uniform picture intensity in a radar system as the system is switched to different range scales.

Another object is to provide an improved method and means for providing substantially uniform image intensity on a cathode ray tube screen with variation of the cathode ray scanning speed.

A further object of the invention is to provide an improved plan-position-indicator (PPI) radar system of the type having different range scales that may be selected at will.

In practicing a preferred embodiment of the invention, the invention is applied to a circuit wherein an unblanking pulse is supplied to the cathode ray indicator tube through capacity coupling. According to said preferred embodiment, instead of operating the circuit either with no direct current restoration or with full direct current restoration, the circuit is operated with partial direct current restoration. In this way, as will be apparent hereinafter, it is possible to avoid changes in picture intensity when switching from one range scale to another.

The invention will be better understood from the following description taken in connection with the accompanying drawing in which:

Fig. 1 is a block and circuit diagram of a radar system of the plan-position-indicator (PPI) type embodying the invention;

Figs. 1A and 1B are circuit diagrams showing modifications of a portion of the circuit shown in Fig. 1;

Fig. 2 is a circuit and block diagram showing in more detail a portion of the system of Fig. 1;

Figs. 3, 4 and 5 are graphs that are referred to in explaining the invention;

Fig. 6 is a group of graphs showing a cathode ray tube characteristic and showing unblanking pulses for two scale ranges as they would be applied to the cathode ray tube grid without any direct current restoration;

Figs. 7, 8 and 9 are further graphs that are referred to in explaining the invention; and

Figs. 10, 11 and 12 are groups of graphs that illustrate for comparison purposes the three cases of unblanking pulses without D.-C. restoration, with full D.-C. restoration, and with partial D.-C. restoration, respectively.

Fig. 1 shows a pulse-echo radar system of the plan-position-indicator or PPI type comprising a radio pulse transmitter 10 which supplies pulses of radio energy through a T-R box 11 to a directive antenna 12. Reflected pulses are received by antenna 12 and passed through the T-R box to a pulse receiver 13. The receiver 13 demodulates and amplifies the signal and supplies it through a coupling capacitor 14 to the cathode 16 of a cathode ray indicator tube 17. The T-R box may be any suitable duplexer.

The cathode ray tube is of the well known type having a long persistence phosphorescent screen 18 commonly

employed in PPI radar systems. The tube further comprises the cathode 16, a control grid 19 and an anode 21.

A rotatable deflecting yoke 20 is mounted on the tube 18 and provided with rings 22 and brushes 23 so that a sawtooth deflecting current may be supplied thereto from a sawtooth deflection and unblanking circuit 24. The sawtooth waves are made to occur in synchronism with the transmitted pulses by means of trigger pulses supplied over leads 25 to the deflection circuit 24.

10 The deflecting yoke 20 is rotated in synchronism with the antenna 12 by any suitable means. In the example shown, this is accomplished by means of a motor 26, gearing 27, and mechanical drive connections. The deflecting coil 20 makes one rotation for each rotation of the antenna 12.

15 It will be apparent that in operation the usual PPI deflection pattern is produced, i. e. the electron beam is deflected radially from the center of the screen 18 each time a sawtooth wave is produced. One radial deflection occurs each time a radio pulse is transmitted. This occurs 1000 times per second in the present example. Meanwhile the antenna 12 and yoke 20 make about one rotation every three seconds.

The cathode ray tube 17 is biased substantially to beam 25 cut-off between the radial deflections by a biasing voltage indicated at C—. During each radial deflection the cathode beam is unblocked by an unblanking pulse supplied from the circuit 24 through a coupling capacitor 31 to the control grid 19.

20 Referring more specifically to the input circuit of the cathode ray tube, it will be seen that the reflected pulse is impressed upon the cathode 16 by means of the coupling capacitor 14 and a cathode resistor 32. The biasing voltage (C—) is applied to the grid 19 through resistors 33 and 34.

25 Partial direct current restoration is provided by means of a diode 36 connected across the resistor 33 with its cathode at the grid end of resistor 33. The diode 36 conducts following the positive portion of the unblanking 30 pulse signal to put a charge on capacitor 31. This charge leaks off slowly through resistors 33 and 34. Full D.-C. restoration, which is not desired, would be obtained if the diode 36 were connected across both of the resistors 33 and 34, i. e., with the diode anode connected as shown 35 and with the diode cathode connected to the grid 19.

30 With the partial D.-C. restoration circuit illustrated, only part of the unblanking pulse voltage is impressed across the diode 36 and thus only partial D.-C. restoration is obtained. The desired percentage of full D.-C. restoration may be obtained by selecting suitable relative values of the resistors 33 and 34.

35 The diode 36 need not be connected exactly as shown in Fig. 1. For example, it may be connected as shown in Fig. 1A.

40 Also, it will be apparent that the circuit of Fig. 1B may be employed. Here the unblanking pulses are applied to the cathode of the cathode ray tube with negative polarity. Also, the diode connection is the reverse of that used in Fig. 1.

45 Before describing the circuit operation more completely reference will be made to Fig. 2 which shows one suitable circuit for the sawtooth deflection and unblanking circuit 24.

The trigger pulse from transmitter 10 is impressed upon 50 a one-shot multivibrator comprising vacuum tubes 37 and 38. This multivibrator is of conventional design.

The switch S1 controls the unblanking pulse width and the sweep rate. For one sweep rate the switch S1 connects the anode of tube 38 to the grid of tube 37 through capacitor C1. For the other two sweep rates the said anode-to-grid connection is through C2 and C3, respectively. The changes in sweep rates result, of course, from the fact that capacitors C1, C2 and C3 have different capacity values.

55 The positive unblanking pulse is taken off the anode circuit of the tube 37 as shown and applied over a conductor 41 and through capacitor 31 to the grid 19 of the cathode ray tube 17.

The sawtooth generating circuit may be any one of 60 several well known circuits. In the example shown, three capacitors 42, 43 and 44 of different capacity

values are provided for the three range scales, respectively. A switch S2 switches in the correct capacitor for the desired range.

The selected one of the capacitors 42, 43 and 44 is charged from a B+ source through a selected one of the resistors 46, 47 and 48, the switch S3 and the resistor 49.

A diode 52 is connected to be normally conducting and to prevent the selected one of capacitors 42, 43 and 44 from acquiring a charge until a positive pulse is put on the cathode of the diode 52. It will be seen that diode 52 is connected across the selected capacitor 43, in the example shown, by way of the cathode resistor 53 of the tube 38.

In operation, a positive pulse, corresponding to the unblanking pulse in time, is impressed upon the cathode of diode 52 at the instant a radio pulse is transmitted from the transmitter 10. This blocks the diode 52, the capacitor 43 begins to charge, and the useful sloping portion of a sawtooth wave appears thereacross. At the end of the positive pulse, diode 52 becomes conducting and discharges the capacitor 43. Thus, a sawtooth wave of the duration of the unblanking pulse is supplied to a sawtooth voltage amplifier 54 each time a radio pulse is transmitted. This time relation is illustrated in Fig. 3.

The resistors 46, 47 and 48 and the switch S3 are not essential but preferably are provided for sweep length control.

The amplified sawtooth wave from amplifier 54 is applied to a sweep driver tube 56 which supplies a sawtooth current wave to the deflecting yoke 20.

Reference will now be made to the graphs of Figs. 4 to 12 for a more complete explanation of the partial D.-C. restoration operation.

Figs. 4 and 5 show sawtooth waves for two different sweep rates or range scales together with the corresponding unblanking pulses. The point to note in these figures is that with respect to the alternating current axis the negative portion of the unblanking signal is less negative for the fast sweep (Fig. 5) than for the slower sweep.

Fig. 6 shows the grid volts-beam current characteristic of the cathode ray tube. It also shows the relation between the unblanking pulses applied to the cathode ray tube grid and the tube characteristic for the case of no D.-C. restoration. Unblanking pulses for both a fast sweep and for a slower sweep are shown for comparison purposes. It will be noted that the fast sweep unblanking pulses drive the cathode ray tube grid the more positive (i. e., less negative) so that the result would be a picture of greater intensity for the short range switch setting than for the longer range switch setting.

Referring next to Figs. 10, 11 and 12, these graphs are of the same kind as shown in Fig. 6 but for comparison purposes shown in Fig. 10 no D.-C. restoration, in Fig. 11 full D.-C. restoration and in Fig. 12 partial D.-C. restoration.

It is found that with full D.-C. restoration as shown in Fig. 11, the picture intensity is less for the short range scales (faster sweeps) than for the longer range scales. This is because the screen is brightened less by a beam sweeping quickly across it than by a beam sweeping slowly across it.

Partial D.-C. restoration as shown in Fig. 12 provides substantially uniform picture intensity for the several range scales. It will be seen that for the faster sweeps the unblanking pulses hold the grid of the cathode ray tube more positive than in the case of the slower sweeps, but not to the extent that exists in the case of no D.-C. restoration.

Figs. 7, 8 and 9 illustrate a specific example of partial D.-C. restoration for three different range scales in accordance with the present invention. In these graphs the broken line A represents the A.-C. axis and the broken line B represents the reference axis or base line for the partial D.-C. restoration. The bottom of the graphs at C is the reference axis or base line for full D.-C. restoration. The voltage values on the graphs indicate, by way of example, how far suitable partial D.-C. restoration departs from full D.-C. restoration. It will be seen that in the example shown there is only a little difference for the faster sweep but a substantial difference for the slower sweeps.

It should be noted that partial D.-C. restoration op-

eration requires less D.-C. restoration than might be expected because on long ranges the pulse receiver is operated at higher gain and the general noise level thus produces an increase in intensity level on the longer ranges. In this example, the receiver noise provides more signal on the cathode 16 of the cathode ray tube 17 which causes more beam current to brighten the screen 18.

From the foregoing it will be apparent that the present invention provides a simple and effective way of maintaining the picture intensity constant as cathode ray tube apparatus such as a radar receiver is switched from one sweep rate or range scale to another.

What I claim to be my invention is:

- 15 1. In combination, a cathode ray tube having input electrodes and a phosphorescent screen, means for biasing said tube substantially to beam current cut-off, generator means for producing a sawtooth deflecting wave and for producing an unblanking pulse during each deflecting wave, means for deflecting the cathode ray of said tube by said deflecting wave, means for applying said unblanking pulses through a capacitor coupling to one of said input electrodes to unblock the cathode ray tube during deflection of the cathode ray, range scale switching means for increasing the slope of the sawtooth deflecting wave and for decreasing the duration of the unblanking pulse, and means for maintaining the picture intensity on said screen substantially constant as the range scale switching means is operated to provide different range scales, said last means including a direct current restorer circuit connected to the input electrode to which said unblanking pulses are applied, said restorer circuit comprising a diode and circuit means for applying only a portion of the unblanking pulse voltage to said diode whereby only a portion of the direct current component of the unblanking pulses is restored.
- 20 2. In pulse-echo distance determining apparatus, a cathode ray indicator tube having input electrodes and a phosphorescent screen, means for biasing said tube substantially to beam current cut-off, deflecting means for deflecting the cathode ray of said tube, generator means for supplying to said deflecting means a sawtooth deflecting wave, means for generating an unblanking pulse and for applying it through a capacitor coupling to one of said input electrodes to cause flow of beam current during the occurrence of said sawtooth deflecting wave, means comprising range scale switching for increasing the slope of the sawtooth deflecting wave to thereby increase the speed of the cathode ray sweep and for decreasing the duration of the unblanking pulses, and means for maintaining the picture intensity on said screen substantially constant when the apparatus is switched from one scale range to a different scale range, said last means including a direct current restoration circuit connected to the input electrode to which unblanking pulses are applied, said restoration circuit including a diode and circuit means for applying only a portion of the full unblanking pulse voltage to said diode whereby the direct current component of the unblanking pulses is only partially restored.
- 25 3. In cathode ray tube apparatus wherein means is provided for switching from one sweep rate to a different sweep rate, a cathode ray indicator tube having input electrodes and a phosphorescent screen, means for producing deflecting waves and for deflecting the cathode ray of said tube by said waves, means for producing unblanking pulses simultaneously with said deflecting waves and for applying them to one of said input electrodes, and means for maintaining the picture intensity on said screen substantially the same for one sweep rate as for a different sweep rate, said last means including a direct current restorer circuit connected to said one input electrode, said restorer circuit including a rectifier and circuit means for only partially restoring the direct current component of said unblanking pulses by an amount such as to maintain said same picture intensity for said different sweep rates.
- 30 4. In a radar system of the plan-position-indicator type and wherein means is provided for switching from one range scale to a different range scale, a cathode ray indicator tube having input electrodes and a phosphorescent screen, means for producing deflecting waves and for deflecting the cathode ray of said tube by said waves, means for producing unblanking pulses simultaneously with said deflecting waves and for applying

them to one of said input electrodes, and means for maintaining the picture intensity on said screen substantially the same for one range scale as for a different range scale, said last means including a direct current restorer circuit connected to said one input electrode, said restorer circuit including a rectifier and circuit means for only partially restoring the direct current component of said unblanking pulses by an amount such as to maintain said same picture intensity for said different range scales.

5. In a pulse-echo radar system of the plan-position-indicator type, means for radiating radio pulses from a directive rotating antenna, means for receiving said pulses after reflection, a cathode ray indicator tube having input electrodes and a phosphorescent screen, means for biasing said tube substantially to beam current cut-off, means for producing a sawtooth deflecting wave and for deflecting the cathode ray of said tube by said wave radially from the center of said screen in synchronism with the pulse radiation, means for rotating said radial deflection in synchronism with said directive antenna, means for generating an unblanking pulse and for applying it through a capacitor coupling to one of said input electrodes to cause flow of beam current during the occurrence of said sawtooth deflecting wave, means for applying said reflected pulses to said other input electrode, means comprising range scale switching for increasing the slope of the sawtooth deflecting wave to
